MANUFACTURE OF PILE FABRICS

Joseph Kubicky, Brandywine Summit, Pa., assignor to Collins & Aikman Corporation, Philadelphia, Pa., a corporation of Delaware

Application May 29, 1934, Serial No. 728,142

26 Claims. (Cl. 139—397)

My invention relates to the manufacture of fabrics having grounds interconnected by warps passing from one of the grounds to the other, and involves the provision of interconnecting warps having, between the grounds, lengths or sections longer than the distance between the grounds during the weaving, thereby permitting the further separation of the grounds from one another after the weaving of the fabric.

10 My improvements are particularly applicable to the manufacture of pile fabrics having uncut pile loops and cut pile tufts of greater height than the pile loops and simulating and improving upon the appearance of cut and uncut pile fabric made in single pieces upon wire looms.

15 By my invention, such simulations of cut and uncut wire-loom fabrics may be made rapidly and economically upon double shuttle looms equipped with a single set of warpwise-extending members or pile gages and a single pair of shuttles, both of the shuttles preferably laying wefts of the same size. Certain of the wefts laid by each of the respective shuttles form face wefts temporarily supported by the warpwise-extending members and providing supports on 20 which are looped pile warps interconnecting the grounds.

25 The face wefts laid by the upper shuttle and the face wefts laid by the lower shuttle lie on opposite sides of the warpwise-extending members and hence are in different planes between the grounds, and each warp length interconnecting the grounds is preferably looped on a face weft laid by the one shuttle and then looped on a face weft laid by the other shuttle between the exit of such warp length from one ground and its entry into the other ground. The warp is preferably again looped on a face weft laid by one shuttle and then on a face weft laid by 30 the other shuttle on opposite sides of the warpwise-extending members in the passage of such warp back to the ground from which it started.

35 The warpwise-extending members preferably consist of stationary thin metallic strips projecting through the loom reed and having free ends terminating within the fabric but adjacent to the fell line thereof. Other suitable members, such as wires or cords, may, however, be used if desired.

40 Preferably each ground is provided with uncut warp pile loops, which may be looped over the wefts forming supports for the ground-interconnecting warps or the same warps may be used for forming short pile loops and for forming 45 ground-interconnecting warp lengths,

5 The apexes of loops on one ground overlap the apexes of loops on the other ground during the weaving of the fabric. When, however, the fabric is woven down toward the take-up rollers far enough to slide off of the free ends of the warpwise-extending members, the grounds are drawn apart the full distance permitted by the unlooping of the ground-interconnecting warp lengths and the uncut loops on one ground are then materially spaced from the uncut loops on the other 10 ground, so that the interconnecting warp lengths may be readily cut by the usual reciprocating cutter on a double plush loom.

15 The characteristic features and advantages of my improvements will further appear from the following description and the accompanying drawings in illustration thereof.

20 In the drawings, Fig. 1 illustrates diagrammatically the weaving, separation of the grounds and cutting of a double pile fabric in accordance with my invention using a plurality of interconnecting warps and a separate loop-forming warp for each ground; Fig. 2 illustrates diagrammatically a section of cut and uncut fabric produced by my invention from one fabric shown in Fig. 1; Fig. 25 3 shows graphs of suitable draws and sequences of shedding operations illustrating how my invention may be utilized with backings woven either "two-and-one" or "one-and-one"; Fig. 4 illustrates diagrammatically the weaving of a 30 dent-width of a fabric in which the same warps form short pile loops on each ground and ground-interconnecting warp lengths which may be cut to form pile tufts; Fig. 4A shows graphs of a 35 suitable draw and shedding operations in weaving yarns as shown in Fig. 4; Fig. 5 illustrates diagrammatically the weaving of a dent-width of fabric complementary to the dent-width of fabric shown in Fig. 4, with which it may be used in suitable dent groupings to produce a fabric 40 having loops and tufts in adjacent dent groups staggered relative to one another; and Fig. 5A shows graphs of a suitable draw and shedding operations in weaving yarns as shown in Fig. 4.

45 The manufacture of fabric in accordance with my invention may be carried out on a usual type of double shuttle loom having shuttles X and X' simultaneously operable in fixed planes to respectively lay wefts above and below stationary warpwise extending members or gages A supported on a fixed cross bar of the loom and extending warpwise through dent spaces of the reed and into the fabric being woven. The gages preferably consist of flat metal strips, since the height of such gages controls the relative heights 50 55

of the uncut loops and of the cut pile tufts formed by cutting the ground-interconnecting warp lengths. The actual heights of the uncut loops and cut tufts from the grounds may be controlled 5 by the let-off mechanism of the loom independently of the height of the gages, which latter act primarily as connecting pins for supporting the face wefts on which the warps are looped.

The loom is provided with a usual type of reciprocal knife Y and with usual take-up or 10 pin rolls Z and Z'.

In weaving the particular fabric shown in Figs. 1 to 3 of the drawings, which is shown by way of illustration only, there are utilized the backing warps B¹ and B² for forming the ground of the upper fabric, the backing warps B³ and B⁴ for forming the ground of the lower fabric, the pile warp P² for forming uncut pile loops on the upper fabric, the pile warp P⁵ for forming uncut 15 pile loops on the lower fabric, and the pile warps P¹, P³, and P⁴ for connecting the grounds of the upper and lower fabrics and which, when cut, form pile tufts projecting above the pile loops formed by the pile warps P² and P⁵ on the upper 20 and lower fabrics. The warp yarn ends in a dent space of the reed may be drawn through heddles mounted in heddle frames 1 to 10 arranged as indicated in the lower diagram of Fig. 3, which indicates the "draw" for a "two-and-one" backing and also the draw for a "one-and-one" backing. The same draw for the pile yarns 25 may be used for either type of backing. The gages A may be fixed to a stationary heddle frame or to a stationary cross bar.

In weaving a repeat of this fabric, the cycle 30 may be considered as starting with the simultaneous laying of the picks or wefts 1A and 1B by the upper shuttle X and the lower shuttle X' respectively; the weft yarns laid by both shuttles 35 being preferably of the same size or count.

The positions occupied by the warp yarns during the laying of the wefts are indicated by the upper diagram of Fig. 3 showing the "up", "middle" or "down" position of each warp during the 40 laying of each pair of picks; each vertical row of squares of the upper diagram indicating the positions of a warp thread symbolized by an arrow in the lower diagram aligned with such row.

During the laying of the picks 1A and 1B, the 45 usual harnesses of the loom so positioned the heddles through which the warp yarns respectively pass as to hold in the upper pile position the warps P¹ and P², hold in the middle pile position the warps P³, P⁴, and P⁵, hold in the upper position 50 of the top shed the ground warp B¹, hold in the lower position of the top shed the ground warp B², hold in the upper position of the bottom shed the ground warp B⁴, and hold in the lower position of the bottom shed the ground warp B³. The 55 weft 1A therefore forms a ground weft in the upper fabric and secures thereto the pile warps P¹ and P², while the weft 1B forms merely a ground weft in the bottom fabric.

During the reverse movement of the shuttles 60 X and X' to lay respectively the picks or wefts 2A and 2B, the harnesses so position the heddles as to hold in the upper pile position the pile warps P¹, P², P³, P⁴, and P⁵, hold in the upper position 65 of the top shed the ground warps B¹ and B², hold in the upper position of the bottom shed the ground warp B⁴, and hold in the lower position of the bottom shed the ground warp B³. Consequently the weft 2A will be laid between the 70 gauges A and the top ground and will provide a

support for the bottom loop warps P⁵ and the ground-interconnecting warps P³ and P⁴. The weft 2B will be laid in the bottom ground when weaving with a two-and-one backing, but may be laid, as indicated by the dotted weft 2B', between 75 the bottom ground and the warp 5 to provide a one-and-one backing, in which event the ground warps will be shedded as indicated in the one-and-one backing draft.

During the laying of the wefts 3A and 3B by 80 the shuttles X and X' respectively, the loom harnesses position the heddles so as to hold in the lower pile position the pile warps P¹, P², P³, P⁴, and P⁵, hold in the upper position of the top shed the ground warps B², hold in the lower position 85 of the top shed the ground warp B¹, and hold in the lower position of the bottom shed the ground warps B³ and B⁴. Consequently the pick or weft 3A forms a ground weft in the top fabric and the pick or weft 3B lies between the bottom ground 90 and the bottom of the gages A and rests against the latter to form a support for the loop pile warp P² of the upper fabric and the ground-interconnecting pile warps P¹ and P⁴.

On the next movement of the shuttles X and 95 X', they respectively lay the ground weft 4A in the upper fabric and the ground weft 4B in the bottom fabric when a two-and-one backing is being woven. During the laying of the weft 4A and 4B, the harnesses of the loom so position the 100 heddles as to hold in the intermediate pile position the pile warps P¹, P², and P⁴, hold in the lower pile position the pile warps P³ and P⁵, hold in the upper position of the top shed the ground warp B², hold in the lower position of the top shed the ground warp B¹, hold in the upper position 105 of the bottom shed the ground warp B³, and hold in the lower position of the bottom shed the ground warp B⁴. Consequently the weft 4A forms merely a ground weft in the upper fabric, 110 or if it is desired to weave a one-and-one backing the weft 4A may be inserted between the upper fabric and the pile warp P² by shedding the back- 115 ing yarns in the manner indicated in the draft of the one-and-one backing. The weft 4B forms 120 a ground weft in the lower fabric and secures therein the bottom pile loop warp P⁵ and the ground-interconnecting pile warp P³ which are 125 looped under the weft 4B.

During the laying of the weft 5A and 5B by 130 the respective shuttles X and X', the loom harnesses so position the heddles as to hold in the upper pile position the pile warps P² and P⁴, hold in the intermediate pile position the pile warps P¹, P³, and P⁵, hold in the upper position of the top shed the ground warp B¹, hold in the lower position of the top shed the ground warp B², hold in the upper position 135 of the bottom shed the ground warp B⁴, and hold in the lower position of the bottom shed the ground warp B³. Consequently the weft 5A forms a ground weft in the upper fabric and secures 140 therein the loop pile warp P² and the ground-interconnecting pile warp P⁴, which are looped over the weft 5A. The weft 5B forms 145 merely a ground weft in the lower fabric.

During the laying of the weft 6A and 6B by 150 the respective shuttles X and X', the loom harnesses so position the heddles as to hold in the upper pile position the pile warps P¹, P², P³, P⁴, and P⁵, hold in the upper position of the top shed the ground warps B¹ and B², hold in the upper position 155 of the bottom shed the ground warp B⁴, and hold in the lower position of the bottom shed the ground warp B³. The weft 6A 160

is laid between the tops of the gages A and the upper ground, and rests upon the gages A to provide a support for the bottom loop pile warp P^5 , the ground-interconnecting pile warps P^1 and P^3 .
 5 The weft $6B$ is laid in the ground of the lower fabric when a two-and-one backing is being woven or is laid between the bottom backing and the loop pile warp P^5 as indicated at $6B'$ when a one-and-one backing is being woven in accordance with the shedding indicated by the one-and-one backing diagram.

During the laying of the wefts $7A$ and $7B$ by the respective shuttles X and X' , the loom harnesses so position the heddles as to hold in the lower pile position the pile warps P^1 , P^2 , P^3 , P^4 , and P^5 , hold in the upper position of the top shed the ground warp B^2 , hold in the lower position of the top shed the ground warp B^1 , hold in the lower position of the bottom shed the ground warps B^3 and B^4 . The weft $7A$ is laid in the ground of the top fabric and the weft $7B$ is laid between the bottom ground and the gages A, against which it bears to support the top pile loop warp P^2 and the interconnecting pile loop warps P^3 , and P^4 .

During the laying of the wefts $8A$ and $8B$ by their respective shuttles X and X' , the loom harnesses so position the heddles as to hold in the middle pile position the pile warps P^2 , P^3 , and P^4 and hold in the lower pile position the pile warps P^1 and P^5 , hold in the upper position of the top shed the ground warp B^2 , hold in the lower position of the top shed the ground warp B^1 , hold in the upper position of the bottom shed the ground warp B^3 , and hold in the lower position of the bottom shed the ground warp B^4 . Consequently, the weft $8A$ forms merely a ground weft in the upper fabric when this fabric is woven with a two-and-one backing. If it is desired to weave the upper fabric with a one-and-one backing the weft $8A$ may be inserted between the upper ground and the pile warp P^2 by shedding the backing yarns in the manner indicated in the graph of the one-and-one backing. The weft 45 $8B$ forms a ground weft in the lower fabric and secures therein the lower loop pile warp P^5 and the ground-interconnecting pile warp P^1 which are looped under the weft $8B$.

During the laying of the wefts $9A$ and $9B$, the ground warps B^1 , B^2 , B^3 , and B^4 and the pile warps P^1 , P^2 , and P^5 occupy the same positions as during the laying of the wefts $5A$ and $5B$, but the warp P^3 is in the upper pile position and the warp P^4 is in the middle pile position, consequently the weft $9A$ forms a ground weft in the upper ground and secures therein the upper pile loop warp P^2 and the ground-interconnecting pile warp P^3 . The weft $9B$ forms merely a ground weft in the lower ground.

60 During the laying of the wefts $10A$ and $10B$, the pile warps and the ground warps all occupy the same positions as during the laying of wefts $2A$ and $2B$, and the weft $10A$ forms a face weft between the top ground and pile gages A and support the lower pile loop warps P^5 and the ground-interconnecting warps P^1 and P^4 . The weft $10B$ forms a ground weft in the lower fabric when weaving the latter as a two-and-one backing, or may be caused to lie between the bottom fabric and the pile loop P^5 as indicated at $10B'$ by shedding the ground warps as indicated in the one-and-one backing graph.

During the laying of the wefts $11A$ and $11B$, the pile warps and ground warps occupy the same 75 relative positions as they do during the laying

of the wefts $3A$ and $3B$. The weft $11A$ merely forms a ground weft in the upper fabric while the weft $11B$ lies between the lower ground and the gages A and bears against the latter to support the upper loop pile warp P^2 and the ground-interconnecting pile warps P^1 and P^3 .

During the laying of the wefts $12A$ and $12B$, the ground warps B^1 , B^2 , B^3 , and B^4 and the pile warps P^1 , P^2 , and P^5 occupy the same positions as during the laying of the wefts $4A$ and $4B$, but the pile warp P^3 is in the intermediate pile position and the pile warp P^4 is in the lower pile position. The weft $12A$ consequently forms merely a ground weft in the upper fabric, when the latter is woven as a two-and-one backing, or lies as an idle pick between the upper ground and the loop pile warp P^2 when the upper fabric is woven as a one-and-one backing by shedding the ground warps as indicated in the one-and-one backing graph. The weft $12B$ forms a ground weft for the bottom fabric and secures therein the lower pile loop warp P^5 and the ground-interconnecting pile warp P^4 .

It will thus be seen that my improvements permit the manufacture of two fabrics face to face 25 at the same time with the ground of the upper fabric on one side of the warp-wise extending members or pile gages A and the ground of the lower fabric on the opposite side of the warp-wise extending members or pile gages A and the securing 30 of a ground-interconnecting pile warp in one ground, the looping of such warp on a weft between the gages and the opposite ground, the further looping of such warp on a weft between the pile gages and the ground in which it 35 originated, and the securing of such ground-interconnecting warp in the opposite ground.

The withdrawal of the fabrics from the ends of the gages A permits the separation of the grounds a distance equal to the distance diagonally across a gage A from a weft on one side thereof to a weft on the other side thereof on both of which the ground-interconnecting warp is looped.

Any desired number and sequence of different 45 ground-interconnecting pile warps may be utilized by starting each of them at an appropriate weft in an appropriate ground.

The same wefts which support and float the ground-interconnecting pile warp lengths between the grounds may serve as face wefts for supporting pile loops of the respective grounds, whose lengths may be regulated by the loom take-off mechanism but is always less than half the length of the ground-interconnecting warp 55 sections.

Any of the warps may be floated, by means of a dobby or Jacquard, to secure desired ornamental effects. Other types of backing weaves or of pile interlacings with the grounds may 60 also be used. The arrangement illustrated in Figs. 1 to 3, however, give a very desirable effect since, as shown in Fig. 2, it provides, in each fabric, rows of cut pile tufts, which may be of three different colors, and uncut loops between 65 each two rows of pile tufts and shorter than the pile tufts.

These cut pile tufts of greater height than the pile loops result from the cutting of the ground-interconnecting pile warps P^1 , P^3 , and P^4 by the usual cutting motion of a double shuttle loom after the fabric has woven down off the ends of the gages A so as to permit the separation of the grounds a distance equal to the distance diagonally between the two wefts on 75

opposite sides of the gages A over which an interconnecting pile warp is looped. In other words, the upper and lower grounds may be separated, prior to cutting, a distance equal to 5 the distance between the wefts 3B and 6A. This separation of the grounds results in the movement of the apexes of the upper and lower loops from the overlapping, but self-separating, relation in which they are woven to a spaced relation 10 permitting cutting of the interconnecting warps P¹, P³, and P⁴ without danger of cutting the loops on the top fabric or on the bottom fabric, as illustrated at the left of Fig. 1.

The projection of the cut pile tufts above the 15 uncut loops may be regulated by varying the width of the gauges A, such width of the gauges determining the relative heights of the uncut loops and the cut pile tufts. But the absolute height of the pile loops and the cut tufts are 20 independent of the width of the gauges A and may be varied by regulating the pile warp letting-off mechanisms.

Instead of using different warps to form the 25 uncut loops and the interconnecting warps which form the cut pile tufts, the same warp may be used for forming uncut loops on one fabric, then forming floating interconnecting warp lengths between the fabrics, and then forming uncut loops on the first fabric and vice versa.

30 If desired, the warp yarns in one group of dents may be so arranged relative to the warp yarns in an adjacent group of dents that a gauge-supported weft may support an uncut pile loop warp of one fabric along a portion of the length 35 of the weft and a ground-interconnecting warp along another portion of the length of the weft. When such ground-interconnecting warp lengths are cut, areas of cut tufts are left in transverse alignment with rows of uncut loops.

40 An illustrative layout for weaving fabric utilizing the same warps for both uncut loops and the pile tufts is shown in Figs. 4, 4A, 5, and 5A, wherein in Figs. 4 and 4A illustrate the interlacing, draw and shedding of yarns in dents of 45 one group, and Figs. 5 and 5A illustrate the interlacing, draw and shedding of yarns in dents of an adjacent group where a fabric is to be patterned by alternating groups of uncut loops and areas of cut tufts weftwise of the fabric. 50 It will, however, be understood that the draw, shedding and interlacing of either Figs. 4 and 4A or of Figs. 5 and 5A may be used alone in making cut and uncut fabric double.

55 In weaving a fabric having groups of uncut pile loops and groups of pile tufts in weftwise alignment, the same double shuttle loom may be used having the shuttles X, X' and the fixed warpwise extending members or gauges A. The warp ends for a dent of one group may be drawn 60 through heddles mounted in heddle frames arranged as shown in the lower diagram of Fig. 4A, the wires A being mounted in a stationary heddle frame 2, the pile warp p¹ being mounted in a heddle frame 2, the pile warp p² being mounted in a 65 heddle of the heddle frame 4, the top backing warps b¹ and b² being mounted respectively in heddles in the heddle frames 7 and 9, and the back warps b³ and b⁴ for the bottom ground 70 being mounted respectively in heddles of the heddle frames 6 and 8.

The warp ends for a dent of an adjacent group 75 may be drawn through heddles mounted in heddle frames arranged as shown in the lower diagram of Fig. 5A, the wires and backing yarns

b¹, b², b³, and b⁴ in this dent being mounted and drawn in the same manner as shown in the lower diagram of Fig. 4A but the pile warps p³ and p⁴ being drawn through heddles in the heddle frames 3 and 5 respectively. 5

The shedding of the warps in a dent of the first group throughout a complete repeat are shown by the upper diagram of Fig. 4A wherein there is shown for each pair of picks the warps that are in an upper position, indicated by a 10 dot, the warps that are in a lower position, indicated by a blank square, and the warps that are in a middle pile position, indicated by a cross.

The shedding of the warps in a dent of the 15 second group throughout a complete repeat are shown in the upper diagram of Fig. 5A wherein there is shown for each pair of picks the warps that are in an upper position, indicated by a 20 dot, the warps that are in a lower position, indicated by a blank square, and the warps that are in a middle pile position, indicated by a cross.

By reference to Figs. 4 and 5 the interlacings of the warps with respect to each pair of picks 25 may be traced.

As will be seen by reference to these diagrams, the pick 1a of the first pair is laid in the upper ground and binds therein the pile warp p² in the dent of one group and binds therein the pile 30 warp p⁴ in the dents of the other group. The weft 1b of the first pair is laid in the ground of the bottom fabric and secures therein the pile warp p¹ in dents of the first group and binds therein the pile warp p³ in dents of the second 35 group.

The weft 2a of the second pair of wefts is laid between the top ground and the gauges A and rests on the latter to support the pile warp p¹ in dents of the first group and to support 40 the pile warp p³ in dents of the second group. The weft 2b of the second pair forms a ground weft in the bottom fabric.

The weft 3a of the third pair forms a ground 45 weft in the top fabric, and the complementary weft 3b is laid between the ground of the lower fabric and the gauges A and rests on the latter and has looped thereon the pile warps p¹ and p² in dents of the first group and has looped thereon pile warp p⁴ in dents of the second group.

The weft 4a of the fourth pair is laid in the ground of the top fabric and secures therein the pile warp p¹ in dents of the first group and secures therein pile warp p⁴ in dents of the second group. The weft 4b is laid in the ground 55 of the bottom fabric and secures therein the pile warp p³ in dents of the second group.

The weft 5a of the fifth pair is laid between the ground of the upper fabric and the gauges and rests on the latter and has looped thereon the pile warps p² in dents of the first group and has looped thereon the pile warps p³ in dents of the second group. The complementary weft 5b forms merely a ground weft in the bottom fabric. 60

The weft 6a of the sixth pair forms merely a ground weft in the top fabric. The complementary weft 6b is laid between the ground of the bottom fabric and the gages A, rests on the latter, and has looped thereon the pile warp p¹ in 70 dents of the first group and has looped thereon the pile warp p⁴ in dents of the second group.

The weft 7a of the seventh pair is laid in the ground of the top fabric and secures therein the pile warp p⁴ in dents of the second group. The 75

complementary weft 7b is laid in the ground of the bottom fabric and secures therein the pile warp p² in dents of the first group and secures therein the pile warp p³ in dents of the second group.

5 The weft 8a of the eighth pair is laid between the ground of the top fabric and the gauges A, rests on the latter and has looped thereon pile warps p¹ and p² in dents of the first group and 10 has looped thereon the pile warp p³ in dents of the second group. The complementary weft 8b merely forms a ground weft in the lower fabric.

15 The weft 9a of the ninth pair forms merely a ground weft in the top fabric. The complementary weft 9b is laid between the ground of the bottom fabric and the gauges A, rests on the latter, and has looped thereon the pile warp p² in dents of the first group and has looped thereon pile warp p⁴ in dents of the second group.

20 The weft 10a of the tenth pair is laid in the ground of the top fabric and secures therein the pile warp p² in dents of the first group and secures therein the pile warp p⁴ in dents of the second group. The complementary weft 10b is 25 laid in the ground of the bottom fabric and secures therein the pile warp p¹ in dents of the first group and secures therein the pile warp p³ in dents of the second group.

25 The weft 11a of the eleventh pair is laid between the ground of the top fabric and the gauges A, rests on such gauges, and has looped thereon the pile warp p¹ in dents of the first group and has looped thereon the pile warp p³ in dents of the second group. The complementary weft 11b forms merely a ground weft in 30 the bottom fabric.

35 The weft 12a of the twelfth pair forms merely a ground weft on the top fabric and the complementary weft 12b is laid between the ground of the bottom fabric and the gauges A, rests on such gauges and has looped thereon the pile warp p² in dents of the first group and has looped thereon pile warps p³ and p⁴ in dents of the second group.

40 The weft 13a of the thirteenth pair is laid in the ground of the top fabric and secures therein the pile warp p² in dents of the first group and secures therein the pile warp p³ in dents of the second group. The complementary weft 13b is 45 laid in the ground of the bottom fabric and secures therein pile warp p¹ in dents of the first group.

50 The weft 14a of the fourteenth pair is laid between the ground of the top fabric and the gauges A, rests on the latter and has looped thereon the pile warp p¹ in dents of the first group and has looped thereon the pile warp p⁴ in dents of the second group. The complementary weft 14b forms merely a ground weft in the 55 bottom fabric.

60 The weft 15a of the fifteenth pair forms merely a ground weft in the top fabric. The complementary weft 15b is laid between the ground of the bottom fabric and the gauges A, rests on such gauges, and has looped thereon the pile warp p² in dents of the first group and has looped thereon pile warp p³ in dents of the second group.

65 The weft 16a of the sixteenth pair is laid in the ground of the top fabric and secures therein the pile warp p² in dents of the first group. The complementary weft 16b is laid in the ground of the bottom fabric, and secures therein the pile warp p¹ in dents of the first group and secures therein the pile warp p⁴ in dents of the second group.

The weft 17a of the seventeenth pair is laid between the ground of the top fabric and the gauges A, rests on such gauges and has looped thereon pile warp p¹ in dents of the first group and has looped thereon pile warps p³ and p⁴ in dents of the second group. The complementary weft 17b merely forms a ground weft in the bottom fabric.

70 The weft 18a of the eighteenth pair lies in the ground of the top fabric. The complementary weft 18b is laid between the ground of the bottom fabric and the gauges A, rests on such gauges and has looped thereon the pile warp p² in dents of the first group and has looped thereon pile warp p⁴ in dents of the second group. This 15 completes a repeat where all the uncut loops on one fabric are made from ends of the same warp, but it will be understood that, if desired, the same warp ends may first form loops on one fabric, then be looped on a pair of picks on opposite 20 sides of the gauges A, then be secured in the second fabric, and then form loops on the second fabric before being returned to the first fabric.

25 It will be understood that as the fabrics weave down towards the take-up rolls and off the free ends of the gauges A, the upper ground and the lower ground are separated a further distance equal to the length of the pile warp sections floating diagonally from a weft on one side of the gauges A to a weft on the opposite side 30 of the gauges A. The width of the gauges A is preferably made sufficiently great that when the grounds are so separated the apexes of the uncut loops which are woven in overlapping, but self-separating, relation are spaced sufficiently from 35 one another to permit the cutting of the pile warp lengths interconnecting the ground of one fabric with the ground of the other fabric. Such cutting may be done by the usual reciprocating cutter of a double shuttle loom.

40 Each of the resulting fabrics has uncut pile loops and cut pile tufts greater in height than the uncut loops.

Having described my invention, I claim:

1. In the manufacture of pile fabric face to 45 face with the ground of one fabric on one side of warpwise extending members having free ends and the ground of the other fabric on the other side of the warpwise extending members, the steps which include—interconnecting said two 50 grounds by temporarily looping cut tuft pile-forming yarn for interconnecting the grounds on wefts of sets of wefts supported free from interlacing with the grounds between the selvages on opposite sides of said members and thereby forming 55 bights of such yarn on opposite sides of said members, weaving off the interconnected portions of said grounds from the ends of said members, spreading the grounds apart so that the yarn sections forming bights on one side of said 60 members are shifted from such positions and the yarn sections which previously lay between the sets of bights provide a zone for cutting said interconnected yarns, and cutting such yarn sections.

65 2. In the manufacture of pile fabric face to face with the ground of one fabric on one side of warpwise extending gauge members having free ends and the ground of the other fabric on the other side of said members of a loom having 70 means for cutting pile yarns interconnecting the grounds, the steps which include—interconnecting said two grounds by temporarily looping pile-forming yarn for interconnecting the grounds on wefts of sets of wefts supported free of interlac-

ing with the grounds between the selvages on opposite sides of said members, weaving off the interconnected portions of said grounds from the ends of said members, spreading the grounds to 5 move the wefts of one set from a plane on one side to a plane on the other side of the second set of wefts, advancing the grounds toward said cutting means, and cutting the pile-forming yarns extending between said grounds in a plane 10 between the final planes of said sets of wefts.

3. In the manufacture of pile fabrics face to face with the ground of one fabric on one side of warpwise extending members having free ends and the ground of the other fabric on the other 15 side of the warpwise extending members, the steps which include—securing a pile warp in one of said grounds, looping said pile warp on a weft between said members and the other of said grounds, then on a weft between said members 20 and said first ground, securing said pile warp in said other ground, each of said pile-forming wefts being free from interlacing with the ground adjacent thereto between selvages thereof, moving said weft off said members, spreading said 25 grounds and moving the last specified weft to a plane between the first specified weft and the second named ground, and cutting said warp between the final planes of said wefts.

4. In the manufacture of pile fabric face to face with the ground of one fabric on one side of warpwise extending members having free ends and the ground of the other fabric on the other side of the warpwise extending members, the steps which include—weaving interconnecting pile 30 forming threads over and under wefts supported on opposite sides of said members, weaving off such interlaced portions of said interconnecting pile-forming threads from the free ends of said members, shifting the weft on one side of the 35 center line of said members to a plane on the other side of the center line of said members by spacing the grounds to expand and extend said interconnecting pile to a greater height than the space separating said grounds at the weaving point, and serving an interconnecting pile-forming 40 thread to form cut pile tufts each having a height in excess of one-half the distance separating the grounds at the weaving point while the aforesaid wefts remain between the grounds.

5. In the manufacture of pile fabrics face to face with the ground of one fabric on one side of warpwise extending members and the ground of the other fabric on the other side of the warpwise 45 extending members having free ends, the steps which include—weaving interconnecting pile-forming threads over and under sets of wefts supported on opposite sides of said members, weaving off such interlaced portions of said interconnecting pile threads from said members, 50 spacing the grounds to move the sets of wefts past one another and to substantially straighten and extend said interconnecting pile-forming threads, and severing said interconnecting pile-forming threads between the final planes of the sets of wefts to form cut pile tufts each having a height in excess of one-half the distance separating the grounds at the weaving point and while the aforesaid wefts remain between the grounds.

6. In the manufacture of pile fabrics face to 60 face with the ground of one fabric on one side of warpwise extending members and the ground of the other fabric on the other side of the warpwise extending members, the steps which include—forming pile loops on each ground and over

individual sets of wefts supported by said warpwise extending members, the apexes of loops formed on one ground projecting between the apexes of loops spaced warpwise of the other ground, interconnecting said grounds by pile-forming warp sections having greater length between said ground than the distance between said ground when said apexes are interposed, spacing the grounds from one another by weaving the fabric off of said members while maintaining substantially constant the warpwise spacing of the loop-forming weft of the respective grounds, and cutting said interconnecting warp sections between the final planes of such sets of wefts. 10

7. In the manufacture of pile fabrics face to face with the ground of one fabric on one side of warpwise extending members and the ground of the other fabric on the other side of the warpwise extending members, the steps which include— 15 forming pile loops on each ground and over sets of individual wefts supported by said warpwise extending members, the apexes of loops on one ground projecting between the apexes of warpwise spaced loops on the other ground, interconnecting said ground by pile warp sections each looped about wefts of both sets and having greater length between said grounds than the distance between said grounds when said apexes are interposed, spacing the grounds from one another by 20 weaving the fabric off said members, moving the wefts of one set past the wefts of the other set to substantially straighten the interconnecting warp section looped about such weft, and cutting said interconnecting warp sections between the 25 final planes of the sets of wefts.

8. In the manufacture of pile fabrics face to face with the ground of one fabric on one side of warpwise extending members and the ground of the other fabric on the other side of the warpwise 30 extending members, the steps which include—securing a pile warp in one of said grounds, looping such pile warp over a weft between said members and the opposite ground, securing said pile warp again to the ground to which it was first 35 secured, looping said pile warp on a weft between said members and the opposite ground, looping said warp on a weft between said members and the ground to which it was first secured, securing said warp to the ground opposite that to which 40 it was first secured, each of said pile-supporting wefts being free from interlacing with the ground adjacent thereto between the selvages thereof, weaving said wefts down off said members, 45 spreading said grounds apart and moving the wefts past one another a distance substantially equal to the length of the interconnecting warp section between them, and cutting such interconnecting warp section between said wefts.

9. In the manufacture of pile fabrics face to 50 face with the ground of one fabric on one side of warpwise extending members and the ground of the other fabric on the other side of the warpwise 55 extending members, the steps which include—forming warp pile loops on each ground, 60 the apexes of the loops on one ground projecting between but being self-separating from the apexes of the loop of the other ground, simultaneously with the formation of such loops laying other pile warps interconnecting the ground of one fabric with the ground of the other fabric after looping said other pile warps around wefts positioned on opposite sides of the warpwise members, spreading the grounds to move the wefts originally laid 65 in a plane on one side of the warpwise members to 70

a plane on the opposite side of the warpwise members, and cutting the interconnecting warps between such planes.

10. In the manufacture of pile fabrics face to face with the ground of one fabric on one side of warpwise extending members and the ground of the other fabric on the other side of the warpwise extending members, the steps which include—forming warp pile loops on each of said grounds, 5 the apexes of the loops on one ground projecting between but being self-separating from the apexes of the loops on the other ground, simultaneously with the formation of such loops laying other pile warp interconnecting the ground of one fabric 10 with the ground of the other fabric after looping said other pile warp around wefts positioned on opposite sides of the warpwise members, each of said pile supporting wefts being free from interlacing with the ground adjacent thereto between 15 the selvages thereof, spacing the ground so that the wefts laid closest to the ground are moved to a position further removed from such ground than from the other ground, and cutting the pile warps interconnecting said ground while the upper and lower wefts on which said warps have 20 been supported on the warpwise extending members remain in the fabric but in planes substantially transposed from the positions in which they were originally laid.
- 30 11. In the manufacture of pile fabrics face to face with the ground of one fabric on one side of warpwise extending members and the ground of the other fabric on the other side of the warpwise extending members, the steps which include— 30 forming warp pile loops on each of said grounds, the apexes of the loops on one ground projecting between but being self-separating from the apexes of the loops on the other ground, simultaneously with the formation of such loops, laying other 35 pile warps interconnecting the ground of one fabric with the ground of the other fabric after looping said other pile warps around sets of wefts positioned on opposite sides of the warpwise members, each of said pile-supporting wefts being 40 free from interlacing with the ground adjacent thereto between the selvages, spacing the grounds and transposing the upper and lower loop-forming wefts, and cutting the said interconnecting pile warps between such wefts and before the removal 45 of such wefts from the fabric.
- 50 12. In the manufacture of pile fabrics face to face with the ground of one fabric on one side of warpwise extending members and the ground of the other fabric on the other side of the warpwise extending members, the steps which include—forming uninterlocking and self-separating warp pile uncut loops over wefts supported on opposite sides of said members, each loop being secured to a single ground interconnecting 55 said grounds with pile warp threads interlaced with sets of wefts which are free from interlacing with the grounds between the selvages and are supported on opposite sides of said members, to provide yarn for cut pile having greater height than said loops, weaving off the weft-supported loops and the interconnecting interlaced pile threads from said members, increasing the spacing between said ground to extend and tension said interconnecting pile threads and transpose 60 each set of wefts from the plane in which it was laid into a plane on the opposite side of said warpwise members, and severing said interconnecting threads between said transposed wefts to form cut pile on the separated ground.
- 70 13. In the manufacture of pile fabrics face to 75
- face with the ground of one fabric on one side of warpwise extending members and the ground of the other fabric on the other side of the warpwise extending members, the steps which include—forming uninterlocking self-separating uncut pile weft loops over wefts supported on opposite sides of said members, each loop being secured to a single ground, interconnecting said grounds with pile warp threads interlaced with sets of wefts which are free from interlacing with the grounds between the selvages and are supported on opposite sides of said members to provide yarn for cut pile having greater height than said loops, weaving off the weft-supported loops and the interconnecting interlaced pile threads from said members, separating the grounds and moving the loop supporting weft laid in a plane on one side of the center line of the warpwise members into a plane on the other side of the center line of the warpwise members and thereby increasing the spacing between said ground to a distance greater than the combined length of a loop on each of said grounds, and severing the interconnecting threads to form cut pile on the separated grounds.
- 25 14. In the manufacture of pile fabrics face to face with the ground of one fabric on one side of warpwise extending members and the ground of the other fabric on the other side of the warpwise extending members, the steps which include—securing the pile warp in a ground, looping such pile warp about a weft between said members and the opposite ground, securing said pile warp in the ground to which it was first secured, looping said pile warp around a weft between said members and the opposite ground, looping said warp around a weft between said members and the ground to which it was first secured, and securing said warp to the opposite ground, said loop-supporting wefts being free from interlacing with said ground between the selvages thereof.
- 35 15. In the manufacture of pile fabrics, the steps which include—weaving a pair of grounds spaced apart, concurrently therewith laying a pair of sets of temporary loop-supporting wefts between said grounds and free from interlacing with ground warps and in planes spaced from one another in a direction normal to said grounds, the temporary loop supporting wefts in one plane being staggered warpwise of the fabric relatively to the temporary loop supporting wefts in the other plane, and looping pile warp yarns, some of which are secured in each of said grounds, about the temporary loop supporting wefts lying between the grounds, pile warp yarns secured to both grounds being looped about certain same wefts in each of said planes, such pile warp yarns looped on the same weft being on the same side thereof so that the pile warp yarns looped on each of such temporary loop supporting wefts are self-separating.
- 45 16. In the manufacture of pile fabrics face to face, the steps which include—weaving a plurality of grounds spaced from one another, concurrently therewith laying two sets of wefts free from interlacing with ground warps, said sets of wefts lying between said grounds and in planes parallel with said grounds and spaced from one another in a direction normal to the grounds, the wefts in one plane being staggered relative to the wefts in the other plane warpwise of the fabric, looping a pile-forming warp secured to one of the grounds about a weft in the plane more remote from such ground, then looping such pile-
- 50 55 60 65 70 75

forming warp and a pile-forming warp secured to the second ground about a weft lying in the plane nearer to the first named ground, both of said warps being looped in the same direction 5 about the same side of said weft, then looping said second named warp about a weft lying in the plane more remote from the first ground, thereafter securing said warp in said grounds, each of said warps crossing the distance between 10 the planes of said sets of wefts at least three times between the points where the warps are secured in the grounds and said warps being self-separating.

17. In the manufacture of pile fabrics, the 15 method of forming elongated pile which includes, temporarily forming a plurality of sequential loops, free of interlacing with the ground, in a pile warp, yarn and supporting said loops at their bights by supported elements lying in different 20 planes which are spaced from one another in a direction normal to the ground and releasing said elements supporting said bights.

18. In the face to face manufacture of pile 25 fabrics having grounds, the steps which include interconnecting the grounds with pile-forming yarn, temporarily forming a plurality of sequential loops, free of interlacing with the grounds, in the pile warp yarn and supporting such loops 30 at their bights by supported elements lying in different planes which are spaced from one another in a direction normal to the grounds, releasing the support of the bights, spreading the grounds, and cutting the interconnecting pile-forming 35 yarn to separate the fabrics.

19. In the face to face manufacture of pile 40 fabrics having grounds, the steps which include forming a pile loop secured at both ends in a single ground, interconnecting the grounds with pile-forming yarn, temporarily forming a plurality 45 of sequential loops, free of interlacing with the grounds, in the pile warp yarn and supporting said loops at their bights by supported elements lying in different planes which are spaced from one another in a direction normal to the grounds, releasing the support of the bights, spreading the grounds, and cutting the interconnecting pile-forming 50 yarn to separate the fabrics.

20. In the face to face manufacture of pile 55 fabrics having grounds, the steps which comprise interconnecting the ground with pile-forming yarn by securing some of the pile-forming yarn in the ground of each fabric, temporarily forming a plurality of sequential loops, free of interlacing with the grounds, in the pile warp 60 yarns and supporting said loops at their bights by supported elements lying in different planes spaced in a direction normal to the grounds, securing said pile yarn in the ground of the fabric opposite to its origin, releasing the support of the bights, and cutting the interconnecting pile-forming 65 yarn to separate the fabrics.

21. In the face to face manufacture of pile 70 fabrics having grounds, the steps which comprise interconnecting the grounds with pile-forming yarn by securing some of the pile-forming yarn in the ground of each fabric, temporarily forming a plurality of sequential loops, free of interlacing with the grounds, in the pile 75 warp yarns and supporting said loops at their bights by supported elements lying in different planes spaced in a direction normal to the grounds, the pile yarn from each ground being supported independent of the tension of the pile yarn from the other ground, securing said

pile yarn in the ground of the fabric opposite to its origin, releasing the support of the bights, and cutting the interconnecting pile-forming yarn to separate the fabrics.

22. In the manufacture of pile fabrics face to 5 face, with the ground of one fabric woven substantially parallel to the ground of the other fabric, the steps which include forming pile loops on each ground, the apexes of the loops formed on one ground being positioned between the apexes of the loops of the other ground and spaced in one direction of the fabric to the apexes of the loops 10 formed on one ground being positioned between the apexes of the loops of the other ground, interconnecting the grounds with cut-pile-forming 15 yarn, temporarily forming a plurality of sequential loops, free of interlacing with the grounds, in such yarn and supporting said loops at their bights in different planes which are spaced from one another in a direction normal to the grounds, releasing the support of the bights, spreading the 20 ground, and cutting the interconnecting pile-forming yarn to separate the fabric.

23. In the manufacture of pile fabrics face to 25 face, with the ground of one fabric woven substantially parallel to the ground of the other, the steps which include forming pile loops on one ground, the apexes of the loops formed on one ground being positioned between the apexes of the loops of the other ground and spaced in one direction of the fabric to the apexes of the loops 30 of the other ground, interconnecting the grounds with cut-pile-forming yarn by securing some of said pile-forming yarn in the ground of each fabric, temporarily forming a plurality of sequential loops, free of interlacing with the 35 grounds, in such yarns and supporting said loops at their bights in different planes spaced in a direction normal to the grounds, securing said pile yarn in the ground of the fabric opposite to its origin, releasing the support of the 40 bights, and cutting the interconnecting pile-forming yarn to separate the fabrics.

24. In the manufacture of pile fabrics face to 45 face, with the ground of one fabric woven substantially parallel to the ground of the other, the steps which include forming pile loops on each ground, the apexes of the loops formed on one ground being positioned between the apexes of the loops and spaced in one direction of the fabric to the apexes of the loops of the other 50 ground, interconnecting the grounds with cut-pile-forming yarn by securing some of the said cut-pile-forming yarn in the ground of each fabric, temporarily forming a plurality of sequential loops, free of interlacing with the grounds, in such yarns and supporting said loops at their bights in different planes, spaced in a direction normal to the grounds, securing said pile yarn in the ground of the fabric opposite to its origin, releasing the support of the bights, spacing 55 the ground from one another to substantially straighten the interconnecting pile-forming threads, and cutting the interconnecting pile-forming 60 yarn to separate the fabrics.

25. In the manufacture of pile fabrics, the 65 method of forming elongated pile which includes securing a pile-forming yarn to the ground of the fabric, temporarily forming a plurality of sequential loops, free of interlacing with the 70 ground, in the pile warp yarn and supporting said loops at their bights by supported elements lying in different planes which are spaced from one another in a direction normal to the ground, securing said pile-forming 75 yarn to a fabric

ground and then releasing said support for the loops.

26. In the face to face manufacture of pile fabrics having grounds, the steps which comprise interconnecting the grounds with pile-forming yarn by securing some of the pile-forming yarn in the ground of each fabric, temporarily forming a plurality of sequential loops in the pile yarn from both grounds, free of interlacing 5 with the grounds, and supporting said loops at

their bights by supported elements lying in different planes spaced in a direction normal to the grounds, said bights of the pile yarn originating from both grounds passing about the same side of the spaced supports, securing said pile 5 yarn in the ground of the fabric opposite to its origin, releasing the support of the bights and cutting the interconnecting pile-forming yarn to separate the fabrics.

JOSEPH KUBICKY. 10
